UNITED STATES PATENT OFFICE.

WILLIAM H. WELCH, OF CLEVELAND, OHIO, ASSIGNOR TO THE CLEVELAND MACHINE & MANUFACTURING COMPANY, OF CLEVELAND, OHIO, A CORPORATION OF OHIO.

DRAWING-PRESS.

1,111,000.

Specification of Letters Patent. Patented Sept. 15, 1914.

Application filed August 8, 1913. Serial No. 783,732.

To all whom it may concern:

Be it known that I, WILLIAM H. WELCH, a citizen of the United States, residing at Cleveland, in the county of Cuyahoga and 5 State of Ohio, have invented certain new and useful Improvements in Drawing-Presses, of which the following is a specification.

My invention relates to improvements in 10 drawing or stamping presses, and more particularly to that class or type which is used for drawing sheet metal into deep dies in forming pans, basins, can covers, and the like, and wherein the blank or sheet to be 15 operated upon is placed over the mouth of the die and there held by an annular clamp or blank holder while the plunger descends within the annular holder and forces the sheet metal into the lower die, thus stamping it or drawing it into the desired form. These actions therefore require that the blank holder should first descend forcibly 20 against the margin of the blank and there pause or dwell, holding the blank firmly upon the die, while the plunger continues 25 to descend within the holder and forces or draws the metal of the blank into the die, thus imparting the proper shape thereto. The holder still remains in its holding position 30 during the up-stroke until the plunger is withdrawn, when the blank holder rises with it to release and permit the removal of the stamped article and leave the press ready to receive the next blank. As generally 35 constructed, these presses are provided with but a single blank holder and plunger, so that in large or heavy stampings requiring several impulses or successive stamping and drawings operations, several presses are required, and where the stamping is required 40 to be heated, it is necessary to re-heat the blank or partially completed stamping between the successive drawing operations, thus impeding the work of completing the 45 final article and perhaps impairing the quality of the final finished product.

The primary object of this invention is 50 to provide a generally improved drawing or stamping press of this class, having a plurality of blank holders and plungers conveniently arranged whereby a plural and successive number of drawing or stamping operations may be performed on a single press and without re-heating the blank or 55 partially completed stamping between the

operations or impulses of the press as above referred to.

With the above mentioned and other objects in view, the invention consists in the novel construction, arrangement, and combination of parts, hereinafter described, 60 illustrated in some of its embodiments in the accompanying drawings, and particularly pointed out in the appended claims.

Referring to the drawings, forming a part 65 of this specification, Figure 1, is a view of the improved press partly in front elevation and partly in vertical section, the blank holders and plungers being at the bottom of their stroke. Fig. 2, a vertical sectional 70 view, taken on line 2-2 of Fig. 1, the plunger shown being elevated by a one-quarter revolution of the crank shaft. Fig. 3, a horizontal sectional view taken on line 3-3 of Fig. 1. Fig. 4, a horizontal sectional 75 view taken on line 4-4 of Fig. 1. Figs. 5, 6, 7, and 8, are diagrammatic views showing the parts in their different successive positions to illustrate different relative positions of the respective blank holders and 80 plungers and their actuating mechanism. Fig. 9, a horizontal sectional view of a modified form taken on the general line indicated by line 3-3 of Fig. 1, in which modification two separate and distinct cross heads or 85 slides are provided, as distinguished from the single slide or cross head as shown in Fig. 3.

Similar numerals of reference designate like parts throughout all the figures of the 90 drawings.

The improved machine comprises a suitable base 1, upon which is mounted a fixed frame 2, forming the bearing for the working parts, said fixed frame being provided 95 with a bed or platen 2^a, adapted to receive and carry the stationary or female dies 3. The stationary dies 3, may be removably mounted upon the bed or platen 2^a, by means of bolts 3^a, adapted to be removably mounted 100 in the T-slots 3^b, of the bed 2^a. The blank holder slide or cross head 4, is slidably mounted between the side or upright members 2^b, of the frame by means of vertical guide members 2^c, forming guide or slide- 105 ways for receiving and containing suitably shaped vertical guide members 4^a, at the ends of the blank holder slide or cross head 4.

As a means for carrying and reciprocating 110

ing the slide or cross head 4, the latter is provided with guide lugs 4^b, at the front and rear sides thereof, said guide lugs being connected to connecting or toggle links 5. The links 5, are connected to crank or lever arms 6^a, projecting from and carried by rock shafts 6, mounted in suitable bearings at the upper part of the frame of the machine and on opposite sides thereof.

10 The shafts 6, are provided at their ends with crank arms 6^b, connected to link members 7, the latter being connected to lugs 8^a, of a cross head or slide 8, said slide 8, being adapted to reciprocate in a vertical direction upon a vertical guide 9, suitably mounted at one end of the frame. The slide or cross head 8, is adapted to be reciprocated by means of a connecting arm 10, said arm 10, being suitably connected at one end to the slide 8, and at the other to a crank arm 11^a, of the driving or crank shaft 11. The crank shaft 11, is provided with cranks 11^b, carrying pitmans of connecting arms 12, the latter being adjustably connected to the 25 plungers operating within the adjustably mounted blank holders carried by the blank holder slide or cross head 4, as hereinafter described.

30 The hollow blank holder frames 13^a, are adjustably connected to and carried by the blank holder slide or cross head 4, by means of adjusting bolts and nuts 14, extending through lugs 4^c, of the slide 4, said blank holder frames 13^a, carrying the blank holders 13, which latter may be secured to the holder frames 13^a, by means of securing bolts 13^b.

40 The plunger frames 15^a, are adapted to reciprocate within the blank holder frames 13^a, through the medium of the pitman or connecting arms 12, to which latter they are adjustably connected through the adjustable connecting bolts 16, and internally threaded connecting members 16^a.

45 The plungers or male dies 15, are removably connected to and carried by the plunger frames 15^a, and may be secured to the latter in any suitable and convenient manner, as for example,—by means of key members 17, as illustrated in Fig. 1 of the drawings. The plungers or male dies 15, are adapted to reciprocate within the blank holders 13, and in proper relative relation thereto, as illustrated in Figs. 5 to 8 of the drawings, said plungers or dies 15, being of suitable form to conform to the subjacent stationary dies 3, in accordance with the operations upon and final form to be given to the stamping, as illustrated in Fig. 60 1, of the drawings.

In the operation of stamping heavy sheet metal articles, the blank 18, may be first heated or annealed, and when the blank holders and plungers are in their uppermost position, as indicated in Fig. 8, of the draw-

ings the operator or workman will place the blank above the right-hand fixed or stationary die so that when the corresponding or coöperating blank holder and plunger are brought down during the working impulse 70 or stroke of the machine, the blank 18, will be given its first or initial form, as illustrated at the right-hand side of Fig. 1, of the drawings, and when the blank holder and plunger have moved upwardly to release the 75 partially formed stamping, the latter may be moved to the next or left-hand die for the next or successive operation and at the same time the operator or attendant may place a new blank above the right-hand die so that 80 as the blank holders and plungers are simultaneously given their downward strokes, the two blanks will be simultaneously operated upon, thus clearly increasing the speed and expediting the stamping operation and without again heating or annealing the blank in the successive stamping operations illustrated in Fig. 1, of the drawings. In passing the partially formed blank from the first or right-hand set of dies to the second or 90 left-hand set of dies, the workman or attendant may dip the partially formed blank in the oil of the oil container or receptacle 19, conveniently located upon the bed or platen 2^a, for this purpose, as shown in Figs. 95 1 and 2, of the drawings.

If desired, a plurality or pair of cross heads 4, may be mounted in the frame 2, as illustrated in Fig. 9, of the drawings, in which instance, the connecting or toggle 100 links 5, may be arranged in pairs as there shown, and each slide or cross head 4, separated by a partitioning member or intermediate guide 2^d, extending between the side members of the main frame 2. 105

From the foregoing description, taken in connection with the accompanying drawings, the operation and advantages of my invention will be readily understood.

Having thus described some of the embodiments of my invention, what I claim and desire to secure by Letters Patent is,—

1. In a drawing press, a compound blank holder slide consisting of a main slide, and a plurality of independent auxiliary slides 115 adjustably mounted therein.

2. In a drawing press, a compound blank holder slide consisting of a main slide, blank holder frames mounted therein, and blank holders detachably connected to said blank 120 holder frames.

3. In a drawing press, a blank holder slide, a plurality of blank holder frames adjustably mounted therein, and a plurality of blank holders detachably carried by said blank holder frames beneath said blank holder slide. 125

4. In a drawing press, a compound blank holder slide or cross head consisting of a main slide, hollow blank holder frames ad- 130

justably mounted therein, blank holders detachably connected to said frames, and plungers mounted within said blank holder frames and blank holders.

5 5. In a drawing press, a frame, a blank holder cross head slidably mounted therein, blank holder frames adjustably mounted within said cross head, blank holders carried by said frames beneath said cross head, and plunger frames and plungers mounted in and adapted to reciprocate within the said blank holder frames and blank holders respectively.

6. In a drawing press, a blank holder cross head provided with vertically extending bearing openings, hollow blank holder frames adjustably mounted in said bearing openings, hollow blank holders detachably connected to said frames, and plunger frames and plungers slidably mounted in said blank holder frames and blank holders respectively.

7. In a drawing press, a main frame, a crank shaft, toggle link mechanism connected to the latter, a plurality of plungers connected to said crank shaft, a blank holder cross head connected to said toggle link mechanism, and hollow blank holders adjustably mounted within said blank holder cross head and surrounding said plungers.

8. In a drawing press, a blank holder slide or cross head provided with bearing openings and having laterally extending guide lugs, hollow blank holder frames mounted in said bearing openings and projecting beneath said cross head, adjusting bolts connected to the frames and extending through

said guide lugs, and hollow blank holders detachably connected to said blank holder frames.

9. In a drawing press, a main frame, a crank shaft, toggle link mechanism connected to the latter, a plurality of plungers connected to said crank shaft, and a compound blank holder slide consisting of a main slide connected to said toggle link mechanism and a plurality of hollow independent auxiliary slides mounted within and adjustably connected to said main slide and surrounding said plungers.

10. In a drawing press, a main frame, a crank shaft, a main slide, a plurality of auxiliary blankholder slides independently and adjustably mounted therein, and a plurality of plunger members mounted in said auxiliary blankholder slides and adjustably connected to said crank shaft.

11. In a drawing press, a main frame, a crank shaft, toggle link mechanism connected therewith, a blank holder cross head carried by said toggle link mechanism, hollow blank holder frames and blank holders mounted in said blank holder cross head, and plunger frames and plungers adapted to reciprocate in said blank holder frames and blank holders, respectively, and adjustably connected to said crank shaft.

In testimony whereof I have affixed my signature in presence of two witnesses.

WILLIAM H. WELCH.
